UNITED STATES PATENT OFFICE.

KARL AUGUST BRAUNING, OF ZAANDAM, NETHERLANDS.

HAND-FIREARM.

No. 884,065.

Specification of Letters Patent.

Patented April 7, 1908.

Application filed April 27, 1907. Serial No. 370,578.

To all whom it may concern:

Be it known that I, KARL AUGUST BRAUNING, a subject of the Queen of the Netherlands, residing at Zaandam, Province of North-Holland, Kingdom of the Netherlands, have invented certain new and useful Improvements in Hand-Firearms; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to hand firearms, and more especially to hand firearms of the recoil-operated automatic type, and consists in certain details of construction hereinafter to be described, and claimed.

Referring to the drawings in which like parts are similarly designated—Figure 1 is a vertical, longitudinal section through the breech-bolt of a firearm constructed in accordance with my invention; Fig. 1^a is a rear elevation thereof; Fig. 2 is a horizontal section before firing; Fig. 3 is a like view, after firing; Fig. 4 is a section similar to Fig. 3, showing a modification; Fig. 5 is a section showing parts in firing position in the gun; Fig. 6 is a vertical, longitudinal section showing a modification of the end of the bolt; Fig. 6^a is an end view thereof; Figs. 7, 8 and 9 are details; Fig. 10 is a horizontal, central section of Fig. 5; Fig. 11 is a section on line a—b, Fig. 10.

Referring to Figs. 5 and 10, the mechanism comprises a breech frame 3 fixed to the usual stock, not shown, and provided with oppositely situated lateral openings 3^a having beveled or cam faces 3^b, the purposes of which will hereinafter be described. The rear end of the barrel 2 is threaded and connected to a sleeve 1 which is likewise provided with lateral openings 1^a capable of registering with those 3^a in the breech frame 3. The rear end of the breech frame is closed by a hollow plug 20 having lugs 21 of a bayonet joint, by means of which the rear end of the breech frame is closed. The barrel 2 and sleeve 1 being rigidly connected, move as a unit through the space, Fig. 10, by reason of the recoil, until they abut against the end of plug 20.

Within the sleeve 1 is the breech-bolt 7 that has movement both with and independ-

ently of the sleeve and is locked to the sleeve and in firing position by means of locking lugs 8 pivoted to the breech bolt, and carries the shell extractor 9 at its forward end. The firing pin 11 is mounted within the breech bolt 7. The breech-bolt 7 is urged forward by a coil spring 5 that at one end seats in the hollow plug 20 and at the other surrounds the rear end d of the bolt, Figs. 5 and 10. This rear end d is preferably a cylinder closed at one end and connected to the breech-bolt by a bayonet joint formed by lugs a⁵ entering suitable grooves at d'. Within the cylindrical rear end d of the bolt is a coil spring b⁴ that surrounds the reduced end of the firing pin 11, and through the pin is a vertical opening 12 through which passes the tail b⁷ of the rectangular cocking lever b³ pivoted at 13 to lateral lugs 13^a on the firing pin 11, the tail of said lever having a beveled face b⁸. Within the opening 12 is a coil spring b⁶ taking against the tail of the lever b³ and tending to hold it down. On the breech-bolt is a stop a³ whose end takes against the nose b⁵ of lever b³.

Mounted over the firing pin 11 by means of journals c² taking into longitudinal grooves 22 in the bolt, is a yoke or equivalent device c, (which constitutes the cocking lever) having arms of equal length, and provided with lugs c' at its upper end, said lugs shown in Fig. 1 as resting on top of the stop a³. The lower end of said yoke takes against a shoulder 19 on the firing pin to move it rearward against the stress of its spring b⁴, so that the nose of lever b³ may drop into position behind the stop a³.

Within a transverse slot 13' in the forward end of the firing pin an exchangeable cam piece b' is secured by means of a pin 14, which cam-piece, when the firing pin is projecting forward, rides between the inwardly turned ends of the bolt-locking lugs 8 to throw them and hold them in their locking recesses or openings in the sleeve 1, while the firing pin is moving forward. These lugs 8 project through the openings 1^a in sleeve 1 into those 3^a in the breech frame.

When the bolt has been thrown forward by spring 5 the tail of the right-angle lever b³ (which constitutes the sear) is over the sear actuating lever h⁴ pivoted at 15 in the breech frame. When the sear actuating lever is moved by the trigger 16, both being held in operative position by spring 17 between them, the forward end of the sear

strikes the bevel face b^8 of the sear b^3 and lifts its nose b^5 from behind the abutment a^3 , thereby releasing the firing pin 11 and permitting the spring b^4 to drive said firing pin against the cartridge. At the same time the yoke c is brought to the position shown in Fig. 5. The gases of explosion drive the bolt rearward, and in so doing the ejector 9 draws the cartridge from the end of the barrel 10 and compresses spring 5.

During the rearward movement of the bolt the upper end of the yoke c is forced forward by the forward inclined face of the rail h' fixed in the path of said yoke c , which 15 rides under the rail h' and the latter thereby compels the yoke c to assume the inclined position shown in Fig. 1, the lower end of the lever engaging shoulder 19 on the firing pin and forcing it rearward against its spring 20 b^4 , permitting the sear b^3 under the influence of its spring b^6 to drop behind the stop a^3 . The bolt is then automatically projected forward into the firing position ready for the next pull of the trigger 16.

25 During the rearward movement of the barrel 2 and sleeve 1 as a unit, by reason of the recoil, the rounded portion 8^a of the locking lugs 8 strikes the beveled edges 3^b of the opening 3^a in the breech frame 3, 30 causing these lugs to move against the action of their springs 25 to unlock the bolt from the sleeve 1 and permit it to be propelled independently of the sleeve along the guides or rails 26 in the sleeve 1.

35 It will be noted that I have shown the pivoted locking lugs 8 as being perforated, and in Fig. 4 I have shown the firing pin provided with a locking fork b^2 interchangeable with the cam b' , so that when the firing 40 pin is projected forward the tines 1^a and 2^a of the fork b^2 will pass through the perforations 6 and prevent the lugs 8 from entering their recesses. This is to be used with blank 45 cartridges where the powder charge is comparatively small, when the springs 5 and b^4 will be sufficiently strong to hold the bolt during the discharge.

In Fig. 6 I have dispensed with the pivoted locking lugs 8, and have taken off the 50 movable fixed head of the bolt, substituting therefor the rotatable end e of the bolt and providing the same with locking lugs e' taking into suitable recesses in the breech (not shown) and with slots e^3 and e^4 into which 55 take lugs x and y of the interchangeable part 18 secured in the firing-pin by the pin 14. The spiral slot e^3 for the lug x is narrower than the oppositely situated slot e^4 in which the thinner lug y is guided, so that it will not 60 be possible to insert the head e in the end of the bolt in the wrong position. These slots are shown in Fig. 7, and as the firing-pin is driven forward the head will be rotated and the lugs e' will lock it, and the bolt locked 65 thereto, in firing position.

In Fig. 9 I have shown a bolt f as an open case, having a longitudinally slotted tubular shank not provided with locking lugs. The head of this bolt is exchangeable for the one shown in Fig. 7, and is adapted for use when 7 firing blank cartridges. Should the bolt not be thrown completely, from any accidental cause, the beveled end of the sear actuating lever h^4 will then take in front of the tail b^7 of the sear b^3 and the gun cannot be fired, 7 but the bolt 7 will be moved to the rear.

I claim—

1. In a hand firearm, the combination with a bolt, a stationary rail and a spring-actuated firing-pin in the bolt; of a cocking lever pivoted in the bolt and actuated by engagement with the rail when the bolt is retracted, said lever engaging the firing-pin to move it into cocked position, and independent means passing through the firing-pin to hold the firing-pin in cocked position and simultaneously actuated by the cocking lever. 8

2. In a hand firearm, the combination with the bolt, a stationary rail and a spring-actuated firing-pin; of a cocking lever pivoted in the bolt, a spring-urged sear pivoted in the firing-pin, a lug on the bolt engaged by the sear, said cocking lever actuated by engagement with the rail when the bolt is retracted to permit the sear to engage the lug 9 and hold the firing-pin in cocked position.

3. In a hand firearm, the combination with a bolt, a stationary cam rail and a spring-actuated firing-pin; of a lug on the bolt, an angle-lever mounted on the firing-pin, the nose of said lever held by said lug, a yoke pivoted in the bolt and moved by the rail to retract the firing pin and angle lever to lock the pin in retracted position. 1

4. In a hand firearm, the combination with a stationary cam rail, a recoil-operated, spring-propelled bolt and a spring-urged firing-pin in the bolt; of a lug on the bolt, an angle lever whose tail passes through a vertical slot in the firing-pin, a spring in the slot 1 engaging the tail of said lever to normally hold its nose in the path of the lug, and a yoke pivoted in the bolt and cammed down when the bolt is propelled rearward by the explosion gases and its tail engaging the firing pin to move it and the angle lever rearward, whereby the nose of the angle lever will lie behind the lug to hold the pin retracted. 1

5. In a hand firearm, the combination with the bolt; of pivoted locking lugs mounted thereon having perforations in their ends, a firing-pin propelled between the ends, an exchangeable cam carried by the firing-pin to hold the locking lugs in locking position during firing, and an exchangeable forked member to be inserted in the place of said cam, the tines of which forked member enter said perforations to hold the lugs in unlocked position under all conditions of firing. 1

6. In a hand firearm, the combination 1:

with a bolt; of removable, pivoted locking lugs mounted thereon, a firing-pin within the bolt, an exchangeable cam carried by the firing-pin and a removable bolt-head exchangeable for a rotatable bolt-head and corresponding cam.

In testimony that I claim the foregoing as

my invention, I have signed my name in presence of two subscribing witnesses.

KARL AUGUST BRÄUNING.
